UNITED STATES PATENT OFFICE.

GEORGE H. GIBSON, OF MONTCLAIR, NEW JERSEY.

METHOD OF AND APPARATUS FOR DRYING AND SUPERHEATING A VAPOR.

1,168,298.

Specification of Letters Patent. Patented Jan. 18, 1916.

Application filed May 11, 1914. Serial No. 337,629.

To all whom it may concern:

Be it known that I, GEORGE H. GIBSON, a citizen of the United States of America, residing in Montclair, in the county of Essex and State of New Jersey, have invented certain new and useful Improvements in Methods of and Apparatus for Drying and Superheating a Vapor, of which the following is a true and exact description, reference being had to the accompanying drawings, which form a part thereof.

The general object of my present invention is to provide an improved method of, and apparatus for drying a vapor and superheating it, and is especially intended for drying and superheating steam for use in operating steam turbines, and other steam engines.

In a preferred mode of carrying out my invention, I take saturated steam at the ordinary pressure and condition of dryness at which it is supplied by the boilers of a modern power plant, and expand this steam sufficiently to convert an appreciable portion of the initial potential or pressure energy of the steam into kinetic or velocity energy. I utilize the velocity thus imparted to the steam to separate out of the steam the water particles carried by the steam, in the manner, for instance, in which water is separated out of steam by ordinary centrifugal separators. After the steam is thus dried, I adiabatically recompress the steam to a pressure equal, or approximately equal to its original pressure, as by passing it through a suitable recompressing nozzle or passage.

As the steam expands adiabatically, a portion of the steam condenses, and the heat of vaporization of the condensed steam augments the energy of the uncondensed steam. At the end of its expansion the steam is freed not only from the water which may have been originally admixed with the saturated steam, but also from the water of condensation formed during the expansion. The steam at the beginning of the recompressing operation is saturated and consequently becomes superheated as recompression proceeds, and in practice a very considerable amount of superheat may thus be obtained. The expansion and recompression should not only be adiabatic, but should also be as nearly isentropic as is practically feasible, and in practice may be substantially isentropic.

The apparatus required in carrying out my invention is very simple and compact. Practically all that is needed is an expanding nozzle, a recompressing nozzle, and provisions at or adjacent the connected ends of these nozzles for changing the direction of flow of the steam, and collecting and disposing the liquid particles ejected by reason of their inertia from the steam as the latter has its direction changed. The simplicity and efficiency of the apparatus required permits of its use in many ways where the use of ordinary forms of superheating apparatus heretofore employed is not feasible at all or is open to many objections. In particular, my invention is readily applicable to the successive superheating of the steam as it passes from one stage to another of a multistage turbine.

The various features of novelty which characterize my invention are pointed out with particularity in the claims annexed to and forming a part of this specification. For a better understanding of the invention, however, and of the advantages possessed by it, reference should be had to the accompanying drawings and descriptive matter, in which I have illustrated and described preferred and novel forms of apparatus for carrying out my novel method.

Of the drawings: Figure 1 is a sectional plan, the section being taken on the line 1—1 of Fig. 2; Fig. 2 is an elevation, partly in section, on the line 2—2 of Fig. 1; Fig. 3 is a heat diagram; Fig. 4 is an elevation of another form of apparatus; Fig. 5 is a section on the line 5—5 of Fig. 4; and Fig. 6 is a partial sectional elevation of a steam turbine incorporating provisions for drying and superheating steam in accordance with the present invention as it passes from one stage to another of the turbine.

The apparatus shown in Figs. 1 and 2 comprises essentially an expanding nozzle A, a recompressing nozzle B, which has its apex or smaller end connected to the apex or smaller end of the nozzle A by the helical passage C. A port C' formed through the lowermost point in the wall of the passage C permits water thrown out against the outer wall of the passage C to pass downward through the pipe D into a suitable trap E.

The thermo and kinetic changes occurring in the steam as it passes through the appa-

110

ratus shown in Figs. 1 and 2, is illustrated by the diagram shown in Fig. 3. In this diagram the entropy of the steam is represented by distances measured parallel to the line X, and the total heat of steam is represented by the distances measured parallel to the line Y. While the entropy and total heat of the steam represented by any point in the diagram increases when the distance of the point from the lines Y and X, respectively, is increased, the lines Y and X do not represent zero entropy and total heat units, respectively. On the contrary, the line Y represents an entropy of 1.50 and the line X represents a total heat of 1100 B. T. U. In the diagram shown in Fig. 3, P', P² and P⁴ are pressure curves, the pressure being the same at all points along each of said curves; T', T², and T⁴ are temperature curves or isotherms; and S represents the saturation curve, and S' a quality or moisture percentage curve.

Assuming that the point 1 represents the initial condition of the steam as it enters the expanding nozzle A, and that the steam is saturated, but without free moisture, then the point 1 must lie at the intersection of the saturation curve S by the curve of the initial pressure P'. The changes in the condition of the steam as it passes through the expanding nozzle A, and as the water is ejected therefrom as the steam passes through the channel C, is represented by the vertical isentropic line 1-2 connecting the point 1 with a point 2 beneath it, and by the portion 2-3 of the pressure curve P² extending through the point 2 and intersecting the saturation curve S at the point 3. The change in condition of the steam as it passes through the recompressing nozzle B is represented by the vertical isentropic line 3-4 extending upward from the point 3 to the point 4 where the isentropic line I² intersects the final pressure curve P⁴. In general, the final pressure, indicated by the curve P⁴, will be slightly less than the pressure represented by the curve P'.

In the isentropic expansion of the steam represented by the line 1-2, the total heat of the steam will decrease and a portion of the steam will be condensed. Assuming an initial pressure P' of 200 lbs. absolute, and a pressure P² of 120 lbs. absolute, then the initial total heat of the steam will be 1198.1 B. T. U., and when expanded to the pressure P² will be 1157.3 B. T. U. The heat difference of 40.8 B. T. U., neglecting losses which will be small, will be represented by the kinetic energy of the steam which should have a velocity of approximately 1481 feet per second as it travels through the passage C. On the assumptions made above the percentage of moisture in the steam at the point 2, represented by the quality line S', will be approximately 3.6 per cent. At the point 3

the steam will be saturated and without free moisture. The substantially isentropic recompression of the steam occurring in the passage of the steam through the nozzle B is represented in Fig. 3 by the line 3-4. During this recompression, the pressure of the steam will increase from the pressure P², of 120 lbs. absolute, to a final pressure P⁴, slightly lower than the initial pressure P'. The line 3-4 will be of the same length, or practically of the same length, as the line 1-2. This final pressure is assumed in Fig. 3 to be 195 lbs. absolute, and in practice will be in the neighborhood of that figure. The temperatures T' and T⁴ are the steam table temperatures of 381.9° F. and 341° F., respectively, for saturated steam at 200, and 120 lbs. absolute. Assuming a purely isentropic compression of saturated steam from 120 lbs. absolute to 195 lbs. absolute, the final temperature T⁴ will be 434° F. This means that the steam will then have 54° of superheat, for the temperature of saturated steam at 195 lbs. absolute is 380° F.

The total heat of a pound of saturated steam at 120 lbs. absolute is 1192 B. T. U. Adding to this the heat of 40.8 B. T. U. gained by the conversion of kinetic energy into heat, gives a final total heat of 1232.8 B. T. U. In comparing the final total heat of 1232.8 B. T. U. with the initial total heat of 1198.1 B. T. U., sight must not be lost of the fact that .036 of each original pound of steam has been ejected as water of condensation through the port C', and that nearly all of the difference of some 31.9 B. T. U. between the total heat of each .036 lb. of the ejected water and its initial total heat, when in the form of saturated steam at 200 lbs. absolute, has been added to each .964 lb. of steam entering the nozzle B.

In practice, neither the expansion nor the recompression will be purely isentropic and this tends toward a reduction in the maximum final pressure obtainable. On the other hand, it is probable that some of the kinetic energy of the ejected water will be converted into heat and absorbed by the steam. If the water ejected through the port C' is returned directly to the boiler, the heat thus recovered adds materially to the efficiency of the operation.

It is apparent, of course, that the greater the initial expansion of the steam; *i. e.*, the greater the distance between P' and P², the greater the resultant condensation of steam and the higher the superheat which may be obtained by recompression.

While the use of my invention involves a small loss of pressure in the superheating operation, this is the case also with the ordinary superheaters, in which the superheating is accomplished by means of heat supplied from an external source, and the pressure losses in the two cases are comparable.

in amount. With my invention the superheating can be readily accomplished at the place where the superheated steam is to be used; for instance, the nozzle B may discharge directly to the inlet of a turbine or other steam engine. This has the desirable result of subjecting the steam line fittings, valves, etc., to the lower initial temperature and not to the higher temperature obtained in the superheating operation, thus permitting the use of cast iron in many cases where cast steel would otherwise be required. The heat loss from the steam line will be materially lower, of course, with the lower steam temperature than it would with the higher. Superheating the steam after, instead of before its passage through the steam line reduces the volume of the steam to be handled and consequently, the size of the piping and valves, etc., required. This reduction in volume is partly offset by the fact that, with my invention, a part of the steam passed into the superheater is not superheated, but is ejected as water of condensation. For instance, on the assumptions made above, the steam condensed amounts to 3.6% of the total volume, while the increase in volume, due to superheating the steam 50° F., would be about 6%.

Many different forms of apparatus may be employed in thermo-kinetically drying and superheating steam in accordance with my present invention; and in Figs. 4 and 5 I have illustrated a preferred form of apparatus which I consider to possess substantial advantages over the simpler form of apparatus shown in Figs. 1 and 2. The apparatus shown in Figs. 4 and 5 comprises a casing formed with co-axial annular chambers F and G and central connecting passage H. The chamber F is provided at its periphery with a tangential inlet F'; and the chamber G is provided at its periphery with an outlet G', which preferably, though not necessarily, leads tangentially away from the chamber H. In this apparatus the steam entering the chamber F through the inlet F' passes along a spiral path to the central passage H through which it passes out of the chamber F. As the radius of gyration of this spiral path decreases, the velocity of flow of the steam increases in accordance with the law of conservation of moment of momentum. The increase in velocity and kinetic energy of the steam in passing through the chamber F is accompanied by a corresponding reduction in pressure, and with the chamber F properly designed in accordance with known principles, the expansion of the steam in the chamber F may be made substantially isentropic. The steam issuing from the chamber F will travel through the passage H in a spiral path, and the moisture carried by the steam will be thrown by centrifugal force against the

wall of the passage H, and will flow out of the latter into the annular water collecting chamber H' surrounding and open at its inner edge to the passage H. The water collecting in the chamber H' passes through a pipe H² to a suitable trap E, from whence it may be returned to the boiler or to some other place where hot water may advantageously be used. Water thrown against the peripheral wall of the chamber G may be removed through drain DA and trap EA. The steam entering the chamber G through the passage H passes in a spiral path to the outlet G', and in passing through the chamber G the steam loses kinetic energy and gains in potential energy, in accordance with the same principles which cause the reverse energy transformation occurring in the chamber F. The same principles govern the formation of the two chambers F and G.

The apparatus shown in Figs. 4 and 5 can be used in the form shown, or with slight changes, for many different purposes, as is explained in my prior application Ser. No. 813,241, filed January 20, 1914, wherein I have made generic claims on this type of apparatus.

My thermo-kinetic method of and means for drying and superheating steam may be used for many different purposes, and in Fig. 6 I have illustrated one of the special uses to which my invention may advantageously be put. The special use illustrated in Fig. 6 is the superheating of steam as it passes from one stage to another of a multistage turbine. In the somewhat conventional illustration of Fig. 6, I represents the turbine housing, and J', J² and J³ represent turbine wheels through which the steam is successively passed, K', K² and K³ representing the stationary nozzles through which the steam is delivered to the wheels J', J² and J³, respectively. Interposed between the wheels J' and J² is a superheating device substantially similar in form to the apparatus shown in Figs. 4 and 5, and comprising an expanding chamber f, a recompressing chamber g and a central connecting passage h, all corresponding generally to the chambers F and G and passage H of the apparatus shown in Figs. 4 and 5. The peripheral inlet f' to the chamber f receives the steam leaving the vanes of the wheel J', and the chamber g is open at its periphery to deliver the steam issuing from the chamber g directly to the nozzles K². The water ejected from the steam as it travels through the central passage h collects in a chamber h', from which it is conveyed away to a suitable trap e by means of a pipe d'. As shown in Fig. 6, the superheating provisions employed between the wheels J' and J² are duplicated between the wheels J² and J³. The very important advantages of superheating steam between stages in multistage

turbines are well known. The use of my invention enables this superheating to be accomplished in an efficient manner, and by means of simple and compact apparatus which may be wholly contained within the turbine housing.

While in accordance with the provisions of the statutes, I have illustrated and described the best modes and the best forms of apparatus now known to me for carrying out my invention, it will be apparent to those skilled in the art that many changes may be made in the forms of the modes and apparatus specifically disclosed herein, without departing from the spirit of my invention.

Having now described my invention, what I claim as new and desire to secure by Letters Patent, is:

1. The method of treating a vapor which consists in expanding the vapor to convert some of its potential energy into kinetic energy, separating suspended liquid from the uncondensed vapor, and then, utilizing the kinetic energy of the uncondensed vapor in effecting a recompression of the latter.

2. The method of drying and superheating a vapor which consists in expanding the vapor to convert some of its potential energy into kinetic energy, utilizing the velocity of the vapor and suspended liquid, first in separating the latter from the uncondensed vapor, and then in effecting a recompression of the uncondensed vapor whereby the latter is superheated.

3. The method of drying and superheating a vapor which consists in effecting a substantially isentropic expansion of the vapor, eliminating suspended liquid from the uncondensed vapor, and then utilizing the velocity of the expanded vapor in effecting a

recompression of the uncondensed vapor whereby the latter is superheated.

4. Apparatus for drying and superheating a vapor, comprising in combination, an expansion nozzle and a recompressing nozzle through which the vapor is passed in series, and provisions for eliminating liquid of condensation resulting from the expansion of the vapor in said expansion nozzle and other liquid mixed with the vapor before its recompression in said recompressing nozzle.

5. Apparatus for drying and superheating a vapor, comprising in combination, an expansion nozzle and a recompressing nozzle and a connecting passage, and provisions associated with said passage for eliminating liquid from vapor passing from the expansion nozzle into the recompressing nozzle through said passage.

6. Apparatus for drying and superheating a vapor, comprising in combination, an expanding nozzle, and a recompressing nozzle and a passage connecting said nozzles, all so arranged that vapor expanded in said expansion nozzle follows a curved path through said passage into said compression nozzle, and provisions associated with said passage for collecting and removing water thrown to the outer side of said path by centrifugal action.

7. The method of treating a vapor which consists in expanding the vapor to convert some of its potential energy into mechanical energy, separating the suspended liquid from the uncondensed vapor and then utilizing the mechanical energy in effecting a recompression of the uncondensed vapor.

GEORGE H. GIBSON.
